ORE REDUCING MACHINE

Harlowe Hardinge, York, Pa., assignor to
 Hardinge Company, Incorporated, York, Pa., a
 corporation of New York

Application July 18, 1936, Serial No. 91,402

2 Claims. (Cl. 83—46)

This invention relates to ore reducing machines of the type in which the material is ground or pulverized in a rotating drum supported by hollow or tubular trunnions.

5 An object of the invention is to provide an improved ore reducing machine having a drum formed with a plurality of buckets so constructed that one side of the buckets constitutes means for lifting the material in the bottom of the drum upwardly a predetermined height, and the other portion of the buckets constitutes means for receiving the impact of the material discharged from the buckets at the upper portion of the drum.

10 Another object of the invention is to provide an improved ore reducing machine having a revolvable drum so constructed that a portion of the material fed into the machine for grinding is carried by pockets disposed around the end walls of the drum, and certain of the pockets are provided with means for separating the fines from the coarser particles of the ore segregated from the main body of the ore undergoing reduction in the machine.

15 Another object of the invention is to provide an improved ore reducing machine having a revolvable drum so constructed that the ore is caused to drop on impact mediums in a continuous circuit, and in which means are provided for 20 segregating a portion of the ore within the drum from the main body of the ore undergoing reduction in the machine, so that the finer particles on the segregated portion of ore can be separated and removed from the machine.

25 Another object of the invention is to provide an improved ore reducing machine in which a classifying means is combined with the reducing means so that the fines are removed from the circuit and only the coarser particles which require further reducing are retained in the circuit, whereby great economy in operation is obtained.

Another object of the invention is to provide an improved classifying system for ore reducing 45 machines of the above type in which means are provided within the machine for partially classifying the material and additional classifying means are provided outside of the machine for the final classification of the material so as to 50 improve the character of the product produced and increase the efficiency of the machine.

Another object of the invention is to provide an improved ore reducing machine of the character mentioned, which is simple in construction 55

and reliable and exact in function under all conditions of service.

The invention also comprises certain new and useful improvements in the construction, arrangement and combination of the several parts 5 of which it is composed, as will be hereinafter more fully described and claimed.

In the accompanying drawings:

Figure 1 is a central vertical transverse section through an ore reducing machine embodying the invention;

Fig. 2 is a vertical longitudinal section taken on the line 2—2 of Fig. 1; and

Fig. 3 is a section taken on the line 3—3 of Fig. 1 and Fig. 2.

Referring to the drawings, the improved ore reducing machine comprises a cylindrical drum 11 having end walls 12 and 13.

The end wall 12, which is at the feed end of the drum, has a hollow trunnion 14, and the end wall 13, which is at the discharge end of the drum, has a hollow trunnion 15.

20 The trunnions 14 and 15 are mounted for rotation on roller bearings 35 carried by a suitable supporting structure 16.

25 Any suitable mechanism may be employed for rotating the drum 11. In the present instance the operating mechanism comprises an electric motor 17, the shaft of which carries a gear 18 that is operatively connected to a 30 sprocket 19 fixed to the trunnion 15 of the drum by a chain 20.

Arranged around the interior of the peripheral wall 21 of the drum 11 is a series of members 22. The members 22 constitute means having the 35 combined function of lifting the ore undergoing reduction in the drum upwardly from the bottom portion of the drum while the drum is being rotated, and means for receiving the impact of the ore when the ore falls to the bottom of the 40 drum after being elevated.

In the present embodiment of the invention, as shown in the drawings, the members 22 comprise a radial portion 23 which extends inwardly from the outer peripheral wall of the drum 21 a suitable distance. These radial portions 23 are, as shown in Fig. 1, uniformly spaced apart, and function as lifters or buckets for carrying the material upwardly from the bottom of the drum 11.

Extending from the inner end of the radial portion 23 of each member 22, outwardly towards the peripheral wall 21 of the drum and terminating at the junction of the outer end of the radial portion 23 of the adjacent member 22, is an 55

- arcuate portion 24, the purpose of which will be hereinafter more fully described.
- As shown in Figs. 2 and 3, the ends 25 of the members 22 are spaced a suitable distance from the end walls 12 and 13 of the drum.
- The members 22 may be formed from any suitable material and can be fastened to the peripheral wall 21 of the drum by any suitable method, such as welding.
- 10 Encircling the trunnion 14 and secured to the end wall 12 of the drum is an annular member constituting a shroud 27.
- Also carried by the end wall 13 of the drum is another annular member or shroud 28.
- 15 The shrouds 27 and 28 are frusto-conical in cross section, as shown in Fig. 2, said shrouds having their wall inclined at an angle so that the shrouds taper outwardly from the end walls 12 and 13, respectively.
- 20 The shrouds 27 and 28 are, at their inner edge portions, slightly less in diameter than the interior diameter of the members 22, and the inner edges of the shrouds are spaced apart a distance somewhat less than the length of the members 22, so that the inner portions of the shrouds overlap the extremities of the members 22 a suitable distance, as shown in Fig. 2. The purpose in constructing the parts in this manner will be hereinafter more fully described.
- 30 In the drawings, the shrouds 27 and 28 are shown as composed of two pieces of sheet metal, such as plate steel, the inner portion being of less width than the outer portion and serving as means for reinforcing the outer portion adjacent to the end walls of the drum.
- 35 The shroud 27 surrounds the inlet trunnion 14 of the machine, while the shroud 28 surrounds the outlet trunnion 15.
- The construction of the shrouds 27 and 28 is such that a V-shaped annular compartment is formed at each end of the drum.
- 40 A plurality of flat plates 29, which extend at an angle from the ends of the members 22 outwardly to the end walls of the drum 11, divide the above referred to compartment into a series of pockets 26, the purpose of which will be hereinafter more fully described.
- 45 Openings 30 are formed at intervals around the shroud 28. Overlying each of said openings is a screen 31. Underlying each opening 30 is a chamber 32, the bottom of which is inclined downwardly and outwardly towards the end wall 13, as shown best in Fig. 2. Extending from the bottom of the chamber 32, is a discharge tube 50 55 33. The screening chamber 32 is secured to the shroud 28 and side plates by a reinforcing plate 34.
- 55 In Fig. 1 of the drawings the shroud 28 is shown as being provided with four chambers 32 and tubes 33, and in Fig. 2 the above elements at the lower portion of said shroud are omitted, so as to show the construction of the shroud proper.
- 60 Extending through the trunnion 15 of the machine, is a discharge pipe 36, which supports at its inner end a stationary chamber 37. The chamber 37 has an open upper portion or top.
- Covering the top of the chamber 37 is a screen 38 which is arcuate in front elevation as seen in Fig. 1, and which is inclined at a suitable angle as shown in Fig. 2.
- 65 The chamber 37 is disposed slightly above the axis of the drum 11 and the screened top thereof underlies the ends of the tubes 33 as the same travel around during operation of the machine.
- The outer end of the discharge tube 36 terminates within a classifier device 40, only the end portion of which is shown in Fig. 2. Any suitable type of classifier 40 may be employed. In the present instance I have shown a classifier along the general lines of the rotary wet classifier shown in my Patent No. 1,917,300, granted July 11, 1933. Since the construction and operation of the classifier 40 is well understood it need not be repeated in the instant case. However, leading from the end of the classifier 40 adjacent to the ore reducing machine is a trough or launder 41, by which the oversize material which has been classified is returned to the drum 11 for further reduction.
- In the operation of the device the ore to be ground is fed into the drum 11 by means of a feed trough or launder 43 projecting into the trunnion 14. The material falls into the buckets in the bottom of the drum in the manner shown by the broken lines and arrows in Fig. 2, the material being directed towards the intermediate or central part of the buckets by the inclined surface of shroud 27. The radial portion 23 of the buckets raises the material, as shown in Fig. 1, and the material gradually discharges from the buckets after being raised to a point above the center of rotation of the drum. The material thus discharged from the buckets drops against the arcuate portions 24 of the members 22 and collects in a bed in the manner illustrated in Fig. 1.
- During the operation of the machine a portion of the material collects in the pockets 26 as the mass of material is raised. Due to the construction of the pockets, together with the disposition of the walls of the shrouds 27 and 28, some of the material within the pockets 26 is carried around the end walls of the drum by the pockets 26 a distance further than the material which falls from the buckets proper. The action is such that the material discharged from the buckets mixes with the material spilling out of the pockets 26, so that a considerable intermingling of the different portions of the ore takes place while the drum is rotating.
- Referring to Fig. 1, it will be noted that a bed of material is shown on the member 24 in bucket A, which bucket is disposed at a considerable elevation above the bottom of the drum. The presence of this material in this portion of the machine is due to the fact that the material retained in the pockets 26 at the ends of the above bucket A spills outwardly over the edge of the member 29 and inclined walls of the shrouds 27 and 28, and thus provides a bed on the member 24 for the ore falling into bucket A, as the same moves downwardly toward the bottom of the drum during operation of the machine.
- When the material spills out of the pockets and falls over the lip provided by the inclined walls of the shrouds 27 and 28, the same is directed towards the center of the drum, as shown by the dotted lines in Fig. 2. This action causes the ore to be evenly distributed in the buckets and prevents the ore from hitting heavily against the end walls of the drum. In this way the material moves around the drum in a closed circuit. Excessive wear of the end walls and internal parts of the drum is prevented, and any tendency of the fine and coarse sizes to segregate is eliminated.
- During rotation of the drum, the fines in the material within the pockets 26 near the top of the drum fall through the screens 31, and such fines

are directed towards the screen 38 by the tubes 33. The fines then pass through the screen 38 and collect in the chamber 37 from which they are discharged through tube or launder 36 into the classifier 40. In this way the ore will not pass out of the circuit until it is fine enough to sift through the screens 31 and 38 at the discharge end of the drum.

The fresh feed entering the drum through the shroud 27 intermingles with the ore undergoing reduction which is carried by the members 22, and as the result of this intermingling of ore the finer particles are pushed forwardly towards the discharge end of the drum. In this way there will be a preponderance of finer particles of ore at the discharge end of the drum.

The finer particles together with the water which are delivered to the classifier 40 by the tube or launder 36, are subjected to the classifying action whereby the coarser particles are returned to the drum 11 through the trough or launder 41 for further reduction, and the fines are delivered from the opposite end (not shown) of the classifier 40.

From the foregoing it will be noted that by my invention I have provided an improved ore reducing machine in which means are provided within the drum of the machine for partially classifying the ground material and additional classifying means are provided outside of the drum 11 for the final classification of the material. In actual operation of a machine constructed according to my present invention, the character of the product has been improved considerably over the product of other ore reducing machines heretofore in use, and due to the construction and arrangement of the parts and the manner of grinding the ore in a closed circuit within the drum 11, the power consumption and the frictional wear on the interior of the drum of the machine has been reduced to a minimum, so that the machine can be successfully used for reducing lower grades of ore on a paying basis than would otherwise be possible. In this connection it should be noted that the shrouds 27 and 28, together with the pockets 26 formed by the inclined plates 29, perform the dual function of preventing the ore dropping from the buckets, causing excess friction and wear on the ends of the drum, and these elements also help lift a portion of the ore at the extreme ends of the buckets up and over the top of the drum to help form a protective layer on the back of the buckets which receive the greatest impact of the dropping ore.

From the foregoing description of the operation of the improved machine it will be understood that when so desired the machine can be

constructed with only one of the shrouds 27, 28, and that other modifications can be made in the construction of the machine without departing from the scope of the invention as covered by the claims appended hereto.

Having thus described my invention what I claim is—

1. In an ore reducing machine, a revolvable drum comprising end walls and a peripheral wall, buckets arranged around the interior of the peripheral wall of the drum and midway between the end walls of the drum, said buckets having their end extending towards the end walls of the drum, an annular frusto-conical shroud mounted on the interior of an end wall, the inner edge portion of said shroud abutting the end of the drum being of less diameter than the diameter of the outer edge portion of the shroud, the shroud extending inwardly from the end wall and vertically overlapping the ends of the buckets, a plurality of plates mounted on the interior of the end wall of the drum and contacting the shroud and the ends of said buckets and dividing the end portion of the drum into a plurality of compartments for reception of ore, means formed at intervals in the shroud for removing a portion of the ore from the compartments, and stationary means underlying said ore removing means for discharging from the machine the ore thus removed from the compartments.

2. In an ore reducing machine, a revolvable drum comprising a peripheral wall and end walls providing central openings through the drum, buckets arranged around the interior of the peripheral wall and midway between the end walls, said buckets having open ends extending towards the end walls of the drum, an annular frusto-conical shroud having its apex portion secured to the interior of an end wall and its base portion vertically overlapping the ends of the buckets, a series of flat plates mounted on the interior of the end wall of the drum and contacting the shroud and the ends of said buckets and dividing the end portion of the drum into a plurality of compartments for reception of ore, a plurality of screening chambers disposed at intervals on the shroud for removing a portion of the ore from the compartments, said screening chambers having open ends for discharging material towards the axis of the drum, a stationary screening chamber disposed in the path of ore discharged from said shroud screening chambers, and means connected to said stationary screening chamber for discharging from the machine the ore thus removed from the compartments.

HARLOWE HARDINGE.
